RANGE AND REFRIGERATOR CONSTRUCTION

Jacob Teller and Arthur P. Schulz, Chicago, Ill., assignors, by mesne assignments, to said Jacob Teller and Grace Teller, Chicago, Ill.

Application April 13, 1936, Serial No. 74,215

10 Claims. (Cl. 29—148.2)

The present invention relates to methods of forming cabinet constructions.

More specifically, the invention relates to novel methods of forming frame structures or supporting members or what may be termed the chassis of cabinet constructions.

Cabinets, such as ranges and refrigerators have heretofore been constructed by providing a relatively heavy metal frame of angle-iron construction of channel, T or L shape, in cross section. Such frames required many operations such as notching at the points of bending which necessitated acetylene-welding the corners after bending to provide sufficient strength and eliminate racking of the frames.

Furthermore, such frames were constructed for supporting purposes only and as same were constructed of angle iron, it was necessary to cover such frames in order to provide a finished cabinet of pleasing appearance.

Furthermore, such frames were constructed in such manner that they did not readily admit of different units being supported thereby, thus necessitating separate frames for cabinets provided with differently arranged compartments.

One of the objects of the present invention is to provide a method of frame construction for cabinets whereby a novel frame can readily be provided by relatively few operations.

30 A further object of the invention is to provide a method of constructing a chassis for cabinets formed of ornamental sheet metal whereby same serves not only as a supporting means but also in a decorative or ornamental capacity thereby eliminating the necessity of covering the frame in the finished cabinet.

A still further object of the invention is a novel method of constructing a cabinet chassis from strips of sheet metal, which strips are subjected 40 to a rolling operation to provide the required strength as well as providing an ornamental appearance, bending required lengths of such strips into rectangular shapes and spot-welding the meeting ends thereof, spot-welding sheet metal 45 gussets in the corners of the rectangular members and providing sheet metal supports for supporting the rectangular members in fixed spaced relation to provide a chassis of relatively light yet strong construction and which is endowed with 50 the dual function of serving as a supporting means as well as an ornamental finish for the completed cabinet construction.

Fig. 1 is a perspective view of a gas range constructed in accordance with the present invention.

55 Fig. 2 is a perspective view of a frame or chassis

as embodied in the range construction in Fig. 1 and disclosing the novel method of construction.

Fig. 2A is a sectional perspective view disclosing the cross-sectional configuration of the top frame member and sheet metal top associated therewith.

Fig. 3 is a view similar to Fig. 2 disclosing a modified form of frame or chassis construction.

Fig. 3A is a view similar to Fig. 2A disclosing the cross-sectional configuration of the top frame member of the construction in Fig. 3.

Fig. 4 is a view partly in front elevation and partly in longitudinal vertical section of the range construction disclosed in Fig. 1.

Fig. 5 is a sectional perspective view disclosing the connection between one of the vertical supports and the bottom frame member of the form disclosed in Fig. 3.

Fig. 6 is a sectional perspective view similar to Fig. 5 disclosing a modified form of vertical support and its connection with the bottom frame member of the form disclosed in Fig. 2.

Fig. 6A is a sectional perspective view of a further modified form of vertical support.

Fig. 7 is a transverse sectional view of the splasher back construction.

Fig. 8 is a perspective view of an oven unit.

Fig. 8A is a sectional perspective view disclosing the oven front frame construction and the association of the oven door therewith.

Fig. 8B is a transverse sectional view of the oven front frame construction and associated parts.

Fig. 8C is a fragmental front elevation showing the oven front frame.

The present invention, while relating to cabinet constructions, relates particularly to methods of constructing the chassis or frame work of cabinets such as ranges, refrigerators, etc. which frame work not only functions as a support, but is in itself, a part of the exterior of the cabinet construction and accordingly it is not necessary to cover such frame work in order to create a pleasing external appearance as is the practice now in vogue.

Reference will now be had to the accompanying drawings for a more detailed disclosure of the invention and wherein C (Fig. 1) designates a cabinet construction which is represented as a gas range and which comprises a chassis or frame construction F shown in perspective in Fig. 2, an oven O, a burner compartment B on either side of the oven O and a splashback S together with other elements later described.

The chassis F as indicated in Fig. 2 comprises a top rectangular frame 10, a bottom rectangular

frame 11, a pair of supports 12 for supporting the bottom frame 11 and for supporting the front corners of the top frame 10 and a pair of sheet metal supports 13 for supporting the rear corners 5 of the top frame 10 from corresponding corners of the bottom frame 11.

The frames 10 and 11 are constructed from strips of relatively light gauge sheet metal and are provided with a plurality of longitudinally 10 disposed corrugations 10c and 11c as is indicated in Figs. 2A and 5 which not only add rigidity to well adapt such strips to supporting frame structures but also enhance the appearance of the strips whereby such strips serve not only as supporting frames but also as moldings in the completed cabinet construction.

The strips 10 and 11 are preferably rolled at their opposite edges as indicated at 10d and 11d each of which rolls preferably enclose a rod 10e and 11e which rods further increase the rigidity of the strips and which together with the rolled edges provide strips of channel formation.

The strips 10 and 11 are each bent into a rectangular frame after which the adjacent ends are 25 spot welded.

Each frame 10 and 11 is completed by the provision of gussets 14 and 15 which as is clearly indicated in Fig. 2 comprise sheet metal strips also of corrugated formation as more clearly indicated in Figs. 5 and 6 and which are of somewhat expanded U-shape with the legs thereof spot-welded to the frames 10 and 11. These gussets reinforce the frames 10 and 11 and prevent racking thereof.

35 The vertical portions of the supporting members 12 are disposed at the front corners of the frames 10 and 11 and by the provision of the gussets 14 and 15 triangular spaces are provided at the corners which well serve for the positioning of 40 cast iron filler blocks to which the supporting members 12 are secured in the manner about to be described. The filler blocks 16 are of triangular shape in plan and are provided with suitable lugs 16a and 16b which conform to indentations 45 in the corrugated frames 10 and 11 and gussets 14 and 15 respectively, as is clearly indicated in Figs. 5 and 6, whereby the filler blocks are rigidly maintained in position in the corners of the frames.

50 The filler blocks are of course positioned in the corners of the frames 10 and 11 prior to the spot welding of the gussets 14 and 15 thereto.

The construction of the frames 10 and 11 of a single corrugated or rolled strip as hereinbefore 55 described is highly satisfactory for the usual or average quality product. For a higher quality product, similar frames 10a and 11a as illustrated in Figs. 3, 3A, 4 and 5, may each be constructed by the combination of two pre-formed channels, the outer ones of which are of the same configuration as those already described in frames 10 and 11 and the inner ones of which designated at 10b and 11b respectively have the opposite channel forming flanges thereof telescoped within the channel forming rolled edges 60 of the outer members as is clearly illustrated in Figs. 3A and 5. As is indicated in Fig. 5 the lugs 16a on the filler block 16 are of a somewhat different configuration than those illustrated in Fig. 6 in order to properly seat within the depressions or corrugations of the inner frame members 10b and 11b.

The supporting members 12 are preferably constructed each in two sections, an upper 75 straight section 12a and a lower angular section

12b and the lower filler blocks 16 are each constructed with a hole of the transverse configuration of the supporting member to receive the adjacent ends of the sections 12a and 12b, a shoulder 16c being provided midway the length 5 of the hole to properly seat the adjacent ends of the sections 12a and 12b.

The upper filler blocks which receive the upper ends at the supporting sections 12a do not have a hole therethrough but are each provided with 10 a recess or depression in the bottom thereof to receive the upper end of the corresponding section 12a, as is illustrated in Fig. 4.

The lower supporting sections 12b act as supporting feet and the rear portions thereof may 15 be continued vertically and seated in filler blocks at the rear of the lower frame 11 as can be seen from Fig. 2 or the rear portions of the sections 12b may be supported by brackets 17 suitably supported from the rear corners of the lower 20 frame member 11 as is indicated in Figs. 1, 3 and 4.

The ends of sections 12a and 12b preferably have a force fit in the filler blocks but a set screw 25 may be provided in each of the filler blocks to secure the sections if found necessary. By constructing the supporting members in sections, assembly is greatly facilitated; and the sections 12b can readily be inserted into position after being received by the warehouse or consumer. 30

The supporting members may be constructed of tubular stock as is indicated in Fig. 5 or same may be constructed from rolled channel strips in keeping with the upper and lower frame construction as is indicated in Fig. 6, wherein the 35 supporting member 12' comprises a main or supporting preformed strip 19 and a reinforcing and finishing preformed strip 19a. The supporting members, whether of tubular or strip stock, are constructed of relatively light gauge material 40 and while either form of construction is highly satisfactory from the standpoint of rigidity, the strip stock form shown in Fig. 6 provides supports of the general line formation of the frames 10 and 11 as well as other finishing parts later 45 described and accordingly enhances the appearance of the finished cabinet.

In Fig. 6A is illustrated a modified form of support wherein the main supporting strip 19' is straight between the rolled edges and which 50 is of substantially the same form as the pre-formed strip utilized in the oven front frame construction later described.

By utilizing the dual strip construction of Fig. 6A wherein the main supporting strip is of the 55 same configuration as that utilized in the oven front frame, the number of different forms of channels required is reduced, thereby reducing the cost of the finished cabinet.

The splasher-back S comprises a pre-formed 60 strip or molding 21 of the same configuration as the molding utilized in the frame 10. The strip 21 is of substantially inverted U-form with the ends of the leg portions extending substantially to the lower edge of frame 10 as well as to the 65 upper ends of the sheet metal supports as is indicated in Fig. 1.

Disposed within the strip 21 is a splasher back sheet 22 having a rolled portion 22a and which is constructed of sheet metal and is of dished formation with the flanged edges 22b thereof inserted within a rolled edge of the strip 21 as is clearly shown in Fig. 7.

The range according to the construction in Fig. 1 includes the concealed valve mechanism V and 75

which is concealed by the splasher back sheet 22 as is illustrated in Fig. 7. The sheet 22 is provided substantially centrally thereof with a rectangular opening 23 which is normally closed by a slide 24 which comprises a rectangular sheet of substantially the same extent as opening 23 and is provided with rolled edges 24a in sliding contact with rolled or beaded edges 25a on a valve supporting plate 25.

10 The valve handles or knobs are disposed within plate 25 directly behind the slide 24 and are accessible upon moving the slide to the right or left by means of a suitable manipulating handle 24b.

15 The valves V are disposed in pipes 26 interconnecting the manifold M with the respective corners 27 which are disposed in the burner compartments B.

20 The manifold M is arranged behind the splasher back and the pipes 26 enter the burner compartments B through recesses 28 to the upper ends of the sheet metal supports 13 as indicated in Figs. 2 and 3.

25 The oven O as is illustrated in detail in Figs. 8, 8A, 8B and 8C comprises a front 31 which comprises a strip of sheet metal having rolled edges 31a providing a channel substantially of the same configuration as the channel 19 illustrated in Fig. 6A. This channel strip 31 is bent into rectangular form and secured at the abutting ends 30 by welding. The frame 31 projects beyond the oven front whereby one of the rolled edges 31b forms a rectangular bead which is received in a similarly shaped groove 32 formed in the oven door lining.

35 The oven is completed by double walled top, side and back jackets 33, 34 and 35 respectively, suitable insulating material I being disposed between the jacket walls as indicated. As is indicated in Fig. 8 the jacket ends are so arranged as to permit of various widths and heights of the oven and broiler construction whereby different sized ovens can readily be formed by providing frames 31 of different dimensions.

40 The oven is provided with a horizontal partition P dividing same into an oven compartment and a broiler compartment which are normally closed by doors 36 and 37 respectively.

45 The oven O including the broiler is readily insertable as a unit between the frames 10 and 11 with the opposite sides adjacent the back thereof in contact with flanges 39 on the supports 13 and with the bottom thereof resting on the adjacent edges of sheet metal shelf plates 41 as is clearly indicated in Fig. 4. The top or working surface of the range is provided by suitable sheet metal plates 42 and 43, the former of which is disposed above the oven O and the latter of which are disposed one over each former compartment B.

50 From the foregoing it will be seen that all of the supporting members in the range construction are of relatively light gauge sheet steel which has many advantages over the relatively heavy angle iron of T or L shape heretofore used among which may be enumerated the following: (a) lighter construction; (b) can be assembled with greater facility, and (c) the channels entering into the different frames or supports do not require being covered as in former constructions.

55 While the rolled sheet steel strips provide a lighter chassis than that heretofore obtained by the use of angle iron, the chassis is fully as strong due to the cross-sectional configuration of the strips obtained by the rolling process.

70 In constructing the chassis, the frames 10 and other accessory parts.

11 are each formed from a strip of the rolled sheet steel of a required length which is bent into a rectangular frame by means of a suitable bending jig, after which the cast iron filler blocks 16 are placed in the corners of the frames and the gussets 5 14 and 15 spot-welded to the frames.

15 The supporting members 12 or 12' or at least the upper sections thereof, are then inserted into the filler blocks either by force fit or by using a set screw in each block or both. 10

The supporting members 13 are then secured to the frames 10 and 11 by spot-welding, thus providing the chassis construction illustrated in Fig. 2 or Fig. 3.

20 Under some circumstances it may be found desirable to attach the cast iron filler blocks to the supporting members 12 or 12a prior to assembly whereby special sheet metal gussets peculiar to the shape of the supporting members will not be required. 15

The splasher back is now placed on the chassis and spot-welded thereto after which the oven is placed in position.

25 The spot-welding of the complete chassis is, in order to facilitate assembly preferably carried out automatically by means of a conveyor which progressively carries the different parts to different assembly stations at each of which certain parts are automatically set in place and welded and finally after several operations, the chassis 30 is carried into the spray booth, sprayed with synthetic enamel or black japan, and thereafter baked in a continuous oven.

35 Instead of the progressive automatic spot-welding process above described, portable gun-type spotwelders may be used for the general assembly of the chassis by which the entire chassis can be spot-welded in relatively short time and thereafter the entire assembly may be sprayed with synthetic enamel and then baked. 40

45 The structural members entering into the chassis construction are not only given the requisite strength in the rolling or pre-forming operation, but they possess an aesthetic value as well as serving as supports for the range construction.

50 In using angle iron for the chassis as in former constructions, it was necessary to cover same in order to provide a good appearance of the finished cabinet.

55 With the use of the rolled sheet steel channels, however, it is not necessary to cover same. In fact, the cabinet is given a better appearance by leaving same uncovered as can readily be seen upon inspection of Fig. 1. The channels in accordance with the present invention while fulfilling the requirements of supports are also a part of the exterior finish of the cabinet and provide a cabinet of marked appearance as is well illustrated in Fig. 1.

60 The use of strip sheet steel for the production of frame channels is advantageous in other respects also, as the frames can readily be constructed by the use of comparatively few tools. In fact, rolls, a bending jig and spot welding 65 equipment is all that is required.

65 Furthermore, there is no waste in material as the strip steel can be purchased in rolls and the different channels made by cutting the required length therefrom. In former methods of 70 constructing frames, same were blanked and formed out of sheet steel which occasioned much waste even though the center part of the sheet may have been blanked out for forming legs or

The frame channels also materially aid in various color schemes for the finished cabinet as the channels can be of a color different from the oven and broiler doors as well as the sheet metal shelf members or some of the channels can be of a color different from others of the channels, thus providing an almost unlimited range of color schemes.

The finish of the various parts can be effected in many different ways, in fact the channels can be of stainless steel and the jacket ends and flat rectangular sheets may be synthetic enameled which is a highly desirable finish and which is not well adapted to present day range constructions due to such parts being subject to too great heat which does not occur in the open construction of the present invention wherein such parts are remote from hot-spots.

In the use of two channels, however, the inner one may be of #20 gauge japanned stock, while the outer one may be of .015" thick stainless steel, whereby the cost will not be too great due to the excessive cost of stainless steel. While the double channel frame shown in Figs. 3 and 3A would be somewhat more expensive than the single channel frame shown in Figs. 2 and 2A it possesses some marked advantages as the possibility of damage to the exterior of the frame during assembly and the possibility of replacement of the molding or outer channel member, for the reason that the supports are connected to the inner channel member only whereby the outer channel member or molding can be telescoped over the edge flanges of the inner member after the same has been assembled with the supporting members.

In constructing the supporting members 12' of a pair of channels it makes provision for materially enhancing the appearance of the range in that the outer channel may be of a color different from the inner channel; also this form of construction materially reduces fabrication costs in that a chrome-plating department is not required for the reason that the outer channel may be of .015" thick chromene. In other words, the channel may be constructed from a chrome plated steel strip. The inner channel may be black japanned whereby the supports will have a very pleasing appearance. Other color arrangements may of course be resorted to.

The splasher back being made in two pieces as illustrated in Fig. 7 eliminates the necessity of an expensive drawing-die which would be necessary in the event that it were constructed in one piece. Furthermore, the splasher wall can be made of a material which is not susceptible to hot splashing grease, preferably vitreous enamel, and the pre-formed molding can be chromene or stainless steel.

An additional advantage of this construction is that the parts or edges most susceptible to chipping and damage are made of a material which is not vitreous enameled, but has a lasting and durable finish of its own.

It is to be particularly noted from the foregoing disclosure that the combination oven and broiler unit is separate from the frame or chassis construction and is not connected therewith in any way and has no supporting function.

While we have disclosed certain physical adaptations of our novel methods of construction, same are to be considered as illustrative only, and not restrictive, the scope of the invention being defined in the sub-joined claims.

What we claim as new and desire to secure by U. S. Letters Patent is:—

1. A method of constructing a frame for cabinets which comprises the following steps, bending strips of pre-formed sheet metal into rectangular forms, welding the ends of said strips to provide a pair of rectangular members, disposing perforated filler blocks in the corners of said members, securing gussets to said members for confining the filler blocks in the corners of said members, and inserting adjacent ends of sectional supporting members in the perforations in said filler blocks. 5

2. A method of constructing a cabinet which comprises the following steps, providing a pair of corrugated sheet-steel frames, supporting said frames by sheet-steel tubular supports, at the front thereof and by sheet-steel plates at the rear thereof, disposing sheet-steel units between said frames, and disposing corrugated sheet-steel strips over the outer edges of said sheet-steel plates. 10 15

3. A method of forming cabinet frame structural members comprising the following steps: rolling sheet metal strips to provide longitudinal 25 corrugations intermediate the edges thereof, rolling opposite edges of the sheet metal strips into hollow cylindrical beads, cutting the sheet metal strips into predetermined lengths and bending the resulting sections of the strips into 30 rectangular forms.

4. A method of forming cabinet frame structural members comprising the following steps: rolling sheet metal strips to provide longitudinal corrugations intermediate the edges thereof, 35 rolling opposite edges of the strips into hollow cylindrical beads, inserting reinforcing rods in the hollow beads, cutting the strips thus formed into predetermined lengths, and bending the resulting sections of the strips into rectangular forms. 40

5. A method of forming a cabinet frame structural member, comprising the following steps: rolling opposite edges of a sheet metal strip into hollow cylindrical beads, bending opposite edges 45 of a longitudinally corrugated sheet metal strip for providing a strip of channeled form, and disposing opposite edges of the channel thus formed into frictional contact with the hollow cylindrical beads.

6. A method of forming a cabinet frame structural member, comprising the following steps: forming longitudinal corrugations in a pair of sheet metal strips between the edges thereof, rolling the edges of one of the strips into hollow cylindrical beads for providing a strip of channel formation, bending the edges of the other strip to provide a strip of channel formation, and disposing the channels in face to face relation with the legs of one channel disposed between and in contact with the beads of the other channel. 50 55

7. A method of constructing a cabinet frame which comprises the following steps: forming sheet metal strips with corrugations intermediate their edges, bending the strips into rectangular forms, welding the ends of the strips to provide a pair of rectangular frame members, disposing filler blocks in the corners of the frame members, securing gussets to the frame members for confining the filler blocks in the corners thereof, inserting opposite ends of supporting members in the filler blocks at corresponding sides of the frame members for supporting them in vertically spaced relation, and inserting opposite ends of additional supporting members in the filler blocks 70 75

of one of the frame members for vertically supporting same.

8. A method of constructing a cabinet frame, comprising the following steps: bending longitudinally corrugated sheet metal strips into rectangular forms, welding adjacent ends of the strips to provide a pair of frame members, disposing cast iron filler blocks in interlocking engagement with the frame members in the corners thereof, interlocking gussets with the filler blocks and securing same to the frame members, and disposing sheet metal supporting members in and through the filler blocks for supporting the frame members in vertically spaced relation.
10. A method of constructing a cooking range, comprising the following steps: providing a pair of longitudinally corrugated sheet metal rectangular frames, supporting the frames horizontally and in vertically spaced relation by corrugated sheet metal supports, securing opposite ends of a corrugated sheet metal strip of inverted U-shape to the upper one of said frames, disposing a sheet metal plate having corrugations intermediate its edges within the space defined
15. 9. A method of constructing a cooking range, comprising the following steps: providing a pair of longitudinally corrugated sheet metal rectangular frames, supporting the frames horizontally and in vertically spaced relation by corrugated sheet metal supports, securing opposite ends of a corrugated sheet metal strip of inverted U-shape to the upper one of said frames, disposing a sheet metal plate having corrugations intermediate its edges within the space defined

by one side of the upper of said frames and said strip to provide a splasher back, disposing a fuel control means behind said plate, providing a control means access opening in the corrugated portion of the plate, and providing an opening closing plate of corrugated form slidably disposed over the corrugations of the first mentioned plate.

10. A method of constructing an oven unit, comprising the following steps: rolling opposite edges of a sheet metal strip to provide cylindrical beads, bending the strip into rectangular form and welding opposite ends thereof to provide a rigid frame, securing double walled sheet metal top, bottom, back and side walls to each other and said frame to provide an oven compartment with one of the beads of said frame projecting forwardly of the compartment, providing a door for opening and closing the compartment, and forming a rectangular groove in the inner face of the door for receiving the projecting bead in sealing engagement therewith when the door is closed.

JACOB TELLER.
ARTHUR P. SCHULZ.
